UNITED STATES PATENT OFFICE.

OTTO H. BUSE, OF SHAKER HEIGHTS, OHIO, ASSIGNOR TO THE GRASSELLI CHEMICAL COMPANY, OF CLEVELAND, OHIO, A CORPORATION OF OHIO.

MECHANICAL FURNACE.

Application filed July 5, 1922. Serial No. 573,026.

To all whom it may concern:

Be it known that I, OTTO H. BUSE, a citizen of the United States, and a resident of Shaker Heights, county of Cuyahoga and State of Ohio, have invented a new and useful Improvement in Mechanical Furnaces, of which the following is a specification, the principle of the invention being herein explained and the best mode in which 10 I have contemplated applying that principle, so as to distinguish it from other inventions.

The present invention relates to a new and improved completely mechanical double stage furnace of the type widely used in the manufacture of muriatic acid and other chemicals, in which the materials are first charged onto a furnace floor where they are heated, during which action the material 20 has to be stirred or agitated at intervals to break it up and to allow for the complete reaction that is to be carried out. In such furnaces the agitating or working of the material is a slow and laborious operation 25 which must be performed by hand, the operation usually being carried out by the introduction through ports in the furnace of long heavy tools which are then operated by a man outside of the furnace. It is difficult 30 to handle these tools because of their weight, and it is also difficult for the operator to uniformly agitate the material.

The present invention relates to an improved means for mechanically working the material over on the floor of such a furnace and this means permits of uniform working of an entire furnace floor by a single operator with a considerable saving of labor and the production of a very much 40 more uniform product than has been possible by former methods. To the accomplishment of the foregoing and related ends said invention, then, consists of the means hereinafter fully described and particularly 45 pointed out in the claims.

The annexed drawings and the following description set forth in detail certain mechanism embodying the invention, such disclosed means constituting, however, but one 50 of various mechanical forms in which the principle of the invention may be used.

In said annexed drawings:—

Fig. 1 is a longitudinal vertical section through a furnace for use with which my

present invention is adapted; Fig. 2 is a 55 side elevation of a car provided with means for operating the shovels and stirring means; Fig. 3 is a plan view of such car; Fig. 4 is a front view of the furnace; Fig. 5 is a transverse vertical section through the charging pot and furnace; Fig. 6 is a view of one of the stirring tools; Figs. 7 and 8 are plan and side views, respectively, of another of the tools; Figs. 9 and 10 are similar views of one of the leveling tools; 65 and Figs. 11 and 12 are similar views of a raking tool.

In the ordinary double-stage muriatic furnace the salt is first shoveled into the pot by hand, the pot being adjacent to the muffling furnace and being separate from it. The acid or bisulphate of soda, or a mixture of the two, is then run into the pot and after this pasty mass is heated and thickened the material is pushed out of the pot into the 70 muffle or furnace, this operation being carried out by hand with the use of long, heavy scrapers, which are extremely difficult to handle. After the material is pushed into the furnace proper, it must be spread also 75 by hand and then sliced off the hearth of the furnace, onto which it bakes after being first heated, and must therefore be turned over at regular intervals until the chlorine content of the mass has been reduced to the 80 proper point, and sodium sulphate of the 85 desired degree of purity is obtained.

Such furnaces are commonly 16 to 22 feet long and from 6 to 8 feet wide inside, and the temperature which is maintained varies 90 from 1200 to 1400 degrees F. The working of the material, that is, the charging, leveling, slicing and removing, must be carried out by hand, and the tools used must be of sufficient length to reach to all points of 95 the furnace. The result is that the tools used are extremely heavy and difficult to handle and for proper operation of the furnace more or less skilled operators are required.

The present furnace has been designed to eliminate all of this heavy hand work without the use of mechanical rabbelling or stirring devices, which are used in all of the mechanical furnaces which have appeared 100 on the market up to the present time, which have the disadvantage of requiring iron or steel in the furnace chamber. The weak

point of all mechanical furnaces which employ metal in the furnace chamber proper has been the inability of the metal to stand up continuously under the temperature conditions which are required in the hydrochloric acid atmosphere. A further disadvantage of such furnaces has been their inability to employ the double-stage operation and at the same time produce satisfactory sulphate of soda.

In Fig. 1 there is shown a furnace in which there is a heating floor 1 which is heated by flues 2 and 3 above and below chamber 4. The material is charged onto this floor from a pot 5 which is mounted above the furnace and is connected thereto by means of a vertical conduit 6 which may be closed by means of a damper valve 7 during the operation of the furnace. The mounting of the pot in the present furnace directly above the furnace proper allows for a gravity discharge of the material from the pot directly into the furnace, and also permits of the use of the waste heat from the furnace proper for heating the material in the pot, as will be explained hereinafter. Salt is first introduced to the pot, after which sulphuric acid or bisulphate of soda or a mixture of the two is charged in sufficient quantity to combine with the salt to produce sulphate of soda and hydrochloric acid. This charge is heated until enough of the acid has been driven off to give a heavy pasty mass suitable for the calcining operation. The material is run into the pot 5 through a chute 8 from suitable storage tanks and bins and during the flow of this material from the pot 5 into the chute 8 the material may be agitated by means of suitable scrapers. A plug valve 10 is seated in an opening 11 in the bottom of the pot 5 and this plug seals this opening except during the charging operation. The plug 10 is formed of fire-brick and is sealed against the valve seat in the opening 11 by pouring a small amount of acid resisting material around the top of the plug in the recess formed at the point 12 between the upper beveled surface of the plug and the tapered 50 side wall of the opening.

The furnace chamber 4 on the floor 1 of which the material is spread as it is charged through the conduit 6 is provided with a series of lateral openings 13, 14, and 15 for the discharge of the gas.

The furnace is heated by means of a fire box 90, or other equivalent means, the hot gases passing over the furnace through a passage 91, and then laterally through passages 92 and downward to a passage 93 beneath the hearth of the furnace. A portion of the gas is withdrawn through a port 94 and is passed upwardly through a conduit 95, and then through chambers 96 and 97 in the base of the pot for heating the con-

tents thereof, this gas then being carried to a stack 98. It is unnecessary to describe the construction of the furnace in detail or its operation since furnaces of this same general type are in common use and since the present invention may equally well be applied to furnaces of somewhat different construction and use.

At the front of the furnace is a door 20 which ordinarily covers a port 21. There may be one or more of these doors 20 and there are a sufficient number of doors (see Fig. 4) and the doors are positioned close enough together so that the entire furnace floor may be worked over by the agitating tools when introduced through these doors. Each of the doors 20 is opened by power means in the form of fluid pressure cylinders 110 connected to the doors by chains 111. Air (or other pressure fluid) is supplied to the cylinders through flexible connections (not shown) leading to the operating car to be described presently. In front of the furnace and parallel to the front thereof are tracks 22 on which operate small cars 23 having dump bodies 24 for receiving the salt cake after it has been removed from the furnace. These cars are then run across the front of the furnace to discharge the material.

Mounted parallel to the tracks 22 are other tracks 25 upon which there is mounted a car 26, also adapted to move parallel with the front of the furnace and provided with means for propelling the car over the tracks. This car is shown in Fig. 2 and consists of a rectangular framework mounted upon wheels 27. Mounted on this framework is a fluid pressure motor 28 for driving a shaft 29 which operates a sprocket 30 from which the axle 31 and wheels 27 of the car are driven, the drive being transmitted from the sprocket 30 to the axle by means of a chain 32 and sprocket 33 on the axle. A relatively small motor may be used for this drive since the sprocket 30 is driven through a worm gear 34 and worm 35, the worm being carried on the end of the shaft 29.

Mounted at the front end of the car are two co-operative grooved rolls 40 and 41. These two rolls are mounted closely adjacent to each other and the grooves are formed to receive and firmly support an agitating tool 42. This tool 42 is moved transversely of the direction of travel of the car by means of rolls 43 and 44, of which the upper roll 44 is carried on a shaft 45, which also carries sprockets 46 driven by means of chains 47 from sprockets 48 on a driving shaft 49. This driving shaft 49 is operated by means of a second air motor 50 through a gear 51 on the shaft 49 and a driving pinion 52 on the shaft 53 of the motor.

There is a certain amount of irregularity in the sizes of the different tools, which are operated in the mechanism already described, and to compensate for this difference in the size of the tools the lower roll 43 is pressed upwardly by means of a spring 55, while the upper roll 44 is adjustable by means of a screw 56 controlling the position of the journal 57 in which this roll is carried. To enable the rolls 43 and 44 to grip the tool 42 and operate it against the very considerable resistance of the material in the furnace, a sand box 30 is mounted on the top of the car and sand may be dropped onto the bar 42 through conduits 61 and 61'.

In Fig. 3 there is shown the operator's platform 70, mounted in one corner of the machine, and the controls for operating the two fluid pressure motors 28 and 50 and also for operating the lifting of the various furnace doors 20 are grouped along one side of the operator's platform. In Fig. 2 I have shown the incoming air supply line 71 and a series of four conduits 72, 73, 74 and 25 75, leading to the series of four (or more) furnace doors, while these lines are controlled by means of valves 76, 77, 78 and 79. Air is admitted to the motor 50 through a valve which is controlled by means of a rod 80, link 81 and operating lever 82, which is mounted upon one side of car. Close control of the operation of the car is made possible by the mounting of valves 83 and 84 at the operator's platform for controlling the 30 air conduits leading to the motors 28 and 50 respectively.

The operation of the car is as follows: the car is first moved opposite to one of the doors 20 in the furnace after which the 40 operator causes the opening of this door and then advances the tool 42 through the door and scrapes a path over the furnace floor which is of course equal to the width of the head of the tool. The tool is then 45 retracted, the car is moved a short distance across the opening in the furnace, which the operator is able to judge very accurately after using the apparatus for a short time, in order to bring the operating tool along- 50 side of the furrow which has just been stirred on the floor of the furnace, and the operation is then repeated. This operation is repeated as many times as necessary to 55 completely agitate all of the material which can be reached through a single door, after which the car is moved to the next door and the same operation is carried out until the entire furnace floor has been raked and the material turned over on the floor. After 60 the reaction is complete, a scraping tool is introduced in the same manner and the material is scraped out through the doors of the furnace and into the cars 24. With the present apparatus one operator can completely work over the material in such a

furnace in very much less time than is possible by hand raking and with an important saving in labor cost and time. Furthermore, the material is more uniformly agitated and it can be removed from the furnace very much faster and without letting the furnace cool down between operations.

The various tools for operating on the material on the furnace hearth are shown in Figs. 6 to 12, inclusive. In Fig. 6 there is shown a slice bar for slicing the material from the floor of the furnace, to which it adheres after the first heating. In Figs. 7 and 8 there is shown a turning tool. These tools are run back and forth through the material by means of a car, already described, and act to loosen and turn over the material on the hearth. In Figs. 9 and 10 there is shown a leveler, which consists of a shank 100, carrying two pivoted arms 101. These arms carry at their ends curved shoes 102, which space the arm 101 proper a desired distance from the hearth of the furnace and serve to level off the material when the tools are drawn over the floor. The 80 arms swing between the pins 103 and 104, as indicated.

In Figs. 11 and 12 there is shown a raking tool, consisting of a shank 106 and pivoted rake member 107, which is normally maintained in the position shown in Fig. 12 by means of a spring 108. When pushed into the furnace over the material the rake head swings up, riding on the material, but when returned this head drops down, carrying the material with it and raking it out of the doors of the furnace.

The present furnace has several distinct advantages over the two-stage mechanical furnace now in use, or the two-stage hand furnaces which are the standard type for the manufacture of the material in question. The present furnace allows the crude materials to be charged directly into the pot, eliminating all hand labor which was formerly connected with this operation, and at the same time making the charging operation very much faster than has heretofore been possible. The pot discharges from a central opening, and the interior of the pot is readily accessible for cleaning. Heretofore a central gravity discharge from the pot has been considered impossible because of the difficulties of sealing the discharge opening during the first stage of the operation, but this has been satisfactorily accomplished by means of the plug and sealing means already described. The discharge of the contents of the pot by gravity on to the hearth of the furnace facilitates the even distribution of the material over the hearth by the mechanical stirring and handling tools, and the latter are operated very much faster, and of course with very much less labor than is possible with hand tools. Furthermore,

the tools themselves are in the furnace atmosphere a very much shorter period because of the greater amount of work which can be done by the mechanically operated mechanism than can be done by hand labor in the same period. This decreases very materially the iron content of the finished sulphate of soda, since there is no contamination from the stirring mechanism. Because of the absence of iron in the furnace it is possible to operate it at a higher temperature than is possible with mechanical furnaces containing iron stirrers or hearths, and this gives a salt cake of a very much higher degree of purity, the cake being practically free from excess sulphuric acid and from undecomposed salt.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In mechanism of the character described, the combination of a furnace chamber having a substantially horizontal floor and a door at the level of said floor, a carriage movable in front of said furnace in a plane parallel with the plane of said door, driven rollers mounted on said carriage, a tool engaged between said rollers, said rollers being mounted to position said tool at right angles to the plane of said door, and said rollers being also adapted to actuate said tool into and out of said furnace.

2. In mechanism of the character described, the combination of a furnace chamber having a substantially horizontal floor, an opening in one wall at the level of said floor and a door for closing said opening, a carriage movable in front of said furnace in a plane parallel with the plane of said wall, two pairs of rollers mounted in spaced relation on said carriage in a plane at right angles to the plane of said wall, a tool mounted in said two sets of rollers, and means adapted to actuate said rollers to reciprocate said tool.

3. In mechanism of the character described, the combination of a furnace having an opening in one wall, a movable door normally closing such opening, a carriage mounted adjacent such opening and door, a tool mounted on said carriage, means adapted to actuate said tool through such opening into said furnace, power means adjacent said door for opening the same, and connections between said power means and said carriage whereby said means may be operated from said carriage.

4. In mechanism of the character described, the combination of a furnace having

an opening in one wall, a movable door normally closing such opening, a carriage mounted adjacent such opening and door, a tool mounted on said carriage, power means adapted to actuate said tool into said furnace upon opening of said door, power means adjacent said door for opening the same, and central connections for said two power means, said connections being mounted in proximity to each other on said carriage, whereby said door and tool may be actuated from said carriage.

5. In mechanism of the character described, the combination of a furnace having an opening in one wall, a movable door normally closing such opening, a carriage mounted adjacent such opening and door, a tool mounted on said carriage, power means adapted to actuate said tool into said furnace upon opening of said door, fluid pressure means mounted adjacent said door for opening the same, and connections between said means and said carriage whereby said means may be actuated from said carriage.

6. In mechanism of the character described, the combination of a furnace having a plurality of aligned openings and doors normally closing the same, a carriage movable in a plane parallel with the plane of said doors, a tool mounted on said carriage, means adapted to reciprocate said tool into and out of such openings in said furnace upon opening of said doors, means operable from said carriage for selectively opening said doors, and other means adapted to move said carriage to bring said tool into operative relation with such openings in said furnace.

7. In mechanism of the character described, the combination of a carriage bearing a raised framework thereon, a pair of complementary rollers mounted at one side of said framework, a second pair of complementary rollers mounted in said framework in alignment with said first named pair, said rollers being adapted to receive the shank of a furnace tool, and means adapted to cause one pair of said rollers to firmly engage said shank.

8. In mechanism of the character described, the combination of a carriage bearing a raised framework thereon, a pair of complementary rollers mounted at one side of said framework, a second pair of complementary rollers mounted in said framework in alignment with said first named pair, said rollers being adapted to receive the shank of a furnace tool, and resilient means adapted to press one of said rollers of said last named pair against said shank to engage the same.

9. The combination of two co-operatively mounted rolls, said rolls being provided with grooves in their outer surfaces, such grooves jointly defining a predetermined polygonal

figure, and a tool having a shank operatively and non-rotatably engaged in such grooves.

10. The combination of two co-operatively mounted rolls, said rolls being provided with grooves in their outer surfaces, such grooves jointly defining a predetermined polygonal figure, a tool having a shank op-

eratively and non-rotatably engaged in such joint polygonal groove in said rolls, and means adapted to maintain said rolls in operative engagement with said tool. 10

Signed by me, this first day of July, 1922.

OTTO H. BUSE.
